UNITED STATES PATENT OFFICE.

SAMUEL FRANKLIN GAMMON, OF JACKSONVILLE, FLORIDA, ASSIGNOR TO THE INTERNATIONAL ASSOCIATION OF CIVITAN CLUBS, OF BIRMINGHAM, ALABAMA, A CORPORATION OF ALABAMA.

DESIGN FOR A BUTTON.

Application filed March 16, 1925. Serial No. 12,739½. Term of patent 14 years.

To all whom it may concern:

Be it known that I, SAMUEL F. GAMMON, a citizen of the United States, residing at Jacksonville, in the county of Duval and State of Florida, have invented a new, original, and ornamental Design for Buttons, of which the following is a specification, reference being had to the accompanying drawing, forming part hereof, wherein is shown in—

Fig. 1 a front view, and in Fig. 2 a view in side elevation of a button embodying my invention.

What I claim is:—

The ornamental design for a button, as shown.

SAMUEL FRANKLIN GAMMON.
